ABSTRACT

Covers a method of treating patients exhibiting symptoms of depression by administering to said patients a compound comprising 2-oxo-5-phenyl-4-oxazolidinone.

4 Claims, No Drawings

2-OXO-5-PHENYL-4-OXAZOLIDINONE AS AN ANTI-DEPRESSANT AGENT

BACKGROUND OF THE INVENTION

Patients suffering from depression manifest one or more of a variety of symptoms. Generally speaking a depressed patient feels incapable of dealing with his responsibilities. The predominate symptoms of depression are hypochondria, anoxeria, insomnia, anergia, anhedonia and pessimism. Patients suffering from these symptoms are usually treated with anti-depressants. The present invention provides a method for treating patients exhibiting these symptoms of depression.

BRIEF SUMMARY OF THE INVENTION

This invention relates to a method of treating patients exhibiting symptoms of depression. More particularly, it relates to a method of administering to said patients at least an effective dosage of a composition of 20 2-oxo-5-phenyl-4-oxazolidinone.

DETAILED DESCRIPTION OF THE INVENTION

The just-mentioned compound is known and its preparation disclosed, for example in U.S. Pat. No. 25 2,721,197. Its structure is as follows:

The above compound can be administered orally or by injection. For the latter, solutions or suspensions 35 may be prepared by slurring 1-10 percent of compound in water containing 0.1-2.0 percent of carboxymethylcellulose. Suspensions may also be prepared by using 0.05-0.5 percent tragacanth solutions. For oral administration, tablets, pills, or capsules are easily 40 prepared. Tablets may be prepared to contain between 5 and 25 mg. of the active material together with the usual tableting adjuvants, e.g., coloring agents, flavoring agents, diluents, lubricants, carriers and, if desired, dispersing agents or release retardants. The compound 45 may also be combined with other active compounds such as tranquilizers.

The anti-depression agent disclosed here when administered to mammals such as humans is effective in a dosage range of from about 0.1 to about 200 mg./kg. of 50 body weight daily, either in single or divided dosages. More often the daily dosage range is 0.1-20 mg./kg.

This oxazolidinone compound also exhibits a sedative-tranquilizing activity.

EXAMPLE 1

One excellent way of testing the compounds for its anti-depressant activity is via the modified dopa-test described by G. M. Everett et al., Proc. 1st Int. Symp.

Antidepressant Drugs, p. 164 (1966).

The above-modified dopa-test is based on the following: when dl-dopa is given to untreated mice, no response occurs because of the inactivation of the dopa by endogenous monoamine oxidase. However, if mice are pretreated with a monoamine oxidase inhibitor, such as an oral administration of 40 mg./kg. of paroxyline hydrochloride and then given 200 mg./kg. of dl-dopa orally, along with a known anti-depressant drug, 10 the mice show maximum motor reaction, violent activity, jumping and fighting.

Known anti-depressants such as imipramine and amitriptyline are extremely effective agents in potentiating the dopa response in mice. Thus, the modified dopa test has been found to be usually sensitive and reliable in evaluating the anti-depressant activity of potential drugs.

Here, the 2-oxo-5-phenyl-4-oxazolidinone compound was prepared, administered to mice orally and its activity measured after various periods of time.

The activity of the oxazolidinone compound 4 hours after administration is as follows:

TABLE I

Oral Dose (mg./kg.)	Modified Dopa Test Rating
25	1 - slight activity
50	2 - moderate activity
100	2 - moderate activity
200	3 - marked activity

Eight hours after administration the activity of this compound was shown as follows:

TABLE II

Oral Dose (mg./kg.)	Modified Dopa Test Rating
25	2 - moderate activity
50	2 - moderate activity
100	2 - moderate activity

What is claimed is:

1. A method of treating a patient exhibiting symptoms of depression comprising administering to said patient at least an anti-depressant effective dosage of a composition comprising 2-oxo-5-phenyl-4-oxazolidinone.
2. The method of claim 1 wherein said dosage range is from about 0.1 to about 200 mg./kg. of body weight daily.
3. The method of claim 2 wherein said dosage range is 0.1-20 mg./kg.
4. The method of claim 1 wherein said compound is administered in a unit dosage form in a pharmaceutically-acceptable carrier, said carrier comprising a major portion of said dosage form.
